US0D1055389S

(12) **United States Design Patent** (10) Patent No.: **US D1,055,389 S**
(45) Date of Patent: ** Dec. 24, 2024

(54) **HAND DRYER**

(71) Applicant: **XiaoFeng Zhang**, Wenzhou (CN)

(72) Inventor: **XiaoFeng Zhang**, Wenzhou (CN)

(**) Term: **15 Years**

(21) Appl. No.: **29/952,360**

(22) Filed: **Jul. 15, 2024**

(51) LOC (14) Cl. **28-08**

(52) U.S. Cl.

USPC **D28/54.1**

(57) **CLAIM**

The ornamental design for a hand dryer as shown and described.

DESCRIPTION

FIG. 1 is a perspective view of a hand dryer showing the new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the hand dryer that form no part of the claimed design.

1 Claim, 8 Drawing Sheets
